UNITED STATES PATENT OFFICE.

ALBERT R. PRITCHARD, OF ROCHESTER, NEW YORK.

DESIGN FOR A WATER-KETTLE.

SPECIFICATION forming part of Design No. 25,324, dated March 31, 1896.

Application filed February 29, 1896. Serial No. 581,414. Term of patent 7 years.

To all whom it may concern:

Be it known that I, ALBERT R. PRITCHARD, a citizen of the United States, and a resident of the city of Rochester, in the county of Monroe and State of New York, have invented and produced a new and original Design for Water-Kettles, of which the following is a specification, reference being had to the accompanying drawing, which shows a side elevation thereof.

The leading features of my design consist in the shape and configuration of the water-kettle.

A is the body of the kettle. B is the breast thereof.

C is the cover.

D D are the ears to which the bail is fastened, and E is the spout.

The body A is cylindrical in form.

The breast B is spherical and between the lines b b' has an ogee-bead upon it.

The cover C is provided with a handle C' fastened upon a flattened spherical surface c, surrounded by a bead c', and thence continued another flattened spherical surface c², surrounded by a bead c³.

Between the breast B and the body A is a ring F of spherical beads f in relief.

The spout E is larger at the base than at the tip and has graceful curves on its upper 30 and under sides of long radii.

The handle d is turned down.

The general effect of the upper part of the kettle above the beading F is of a gracefully-broken spherical surface, which, uniting with 35 the cylindrical body and with a line of demarcation between the two parts, consisting of the delicate beading, is pleasing to the eye. It will be noticed that there are no abrupt curves in the body or top and that the clean 40 curves of the spout harmonize gracefully with the remainder of the design.

What I claim is—

The design for a water-kettle, substantially as shown and described.

ALBERT R. PRITCHARD.
